DESIGN FOR COMBINED BOTTLE AND HOLDER OR SIMILAR ARTICLE

Robert B. Karoff, New York, N. Y.

Application May 29, 1944, Serial No. 113,788

Term of patent 3½ years

(Cl. D58—8)

To all whom it may concern:

Be it known that I, Robert B. Karoff, a citizen of the United States and a resident of the city of New York, in the county of New York and State of New York, have invented a new, original, and ornamental Design for Combined Bottle and Holder or Similar Article, of which the following is a specification, reference being had to the accompanying drawing, constituting a part thereof, in which

Fig. 1 is a perspective view of a combined bottle and holder showing my new design;

Fig. 2 is a perspective view of the holder portion only;

Fig. 3 is a perspective view of the bottle member; and

Fig. 4 is a top plan view of the article shown in Fig. 1.

I claim:

The ornamental design for combined bottle and holder or similar article, as shown.

ROBERT B. KAROFF.
